UNITED STATES PATENT OFFICE

ALCADA F. DODSON, OF CHICAGO, ILLINOIS

KEY HOLDER

Application filed June 8, 1927. Serial No. 197,497.

My invention relates to improvements in key holding devices particularly adapted for carrying keys in the pocket. This present invention is a further development and an improvement upon my invention described and claimed in my co-pending application for United States Letters Patent filed March 1, 1926, Serial No. 91,479.

An especial object of this present invention is to provide capacity for a relatively large number of keys, to provide a holder in which a large number of keys can be encased, the holder being so arranged that the keys can readily be swung around to project from the case to facilitate the selection of the particular key wanted at the time; to provide a holder of such a form that two of the holders can be readily combined into a holder of double capacity, and which double capacity holders shall be capable of being arranged in a compact form for conveniently carrying in a pocket.

My invention will be more readily understood by reference to the accompanying drawings forming part of this specification and in which:

Fig. 1, is a plan view of a key holder made in accordance with my invention;

Fig. 2, is a central longitudinal sectional view;

Fig. 3, is a cross-sectional view on the line 3—3 of Fig. 1;

Fig. 4, is a sectional view similar to Fig. 3, but showing the two parts of the holder folded one upon the other;

Fig. 5, is a view similar to Fig. 1, but showing a single member of the holder;

Fig. 6, is a sectional view similar to Fig. 2, but showing the two parts of the holder spread apart as they would appear when the keys are being rotated out of the holder;

Fig. 7, is a sectional view similar to Fig. 2, but showing another manner of hinging the two parts of the holder together;

Fig. 8, is a transverse sectional view on the line 8—8 of Fig. 7;

Fig. 9, is a sectional view similar to Fig. 8, but showing the two parts of the holder folded upon each other;

Fig. 10, is a plan view similar to Fig. 5, but

showing a different form of fastener for retaining the keys in the holder;

Fig. 11, is a fragmentary, longitudinal, sectional view on the line 11—11 of Fig. 10; and

Fig. 12, is a perspective view of the fastener shown in Figs. 10 and 11.

My improved holder in its most simple form, as shown at 1 in Fig. 5, consists of a flat casing adapted to contain a number of keys of the well known flat "Yale" form. The casing is formed of a piece of sheet metal folded or bent to provide two similar flat sides 2 joined together along one side, as at 3. (See Fig. 3). The flat sides 2 are preferably parallel with each other and are spaced apart sufficiently to receive two keys 4 laid flat together, between them. The keys are retained in the holder by a suitable removable retainer, such as a bolt 5, which is placed adjacent to the end of the holder and passes through the usual centrally located holes 5' which are commonly provided in the handles of such keys. In order to retain the sides 2 in parallel condition two of the retaining bolts 5 are provided, one at each end of the holder, and this gives capacity for four of the keys 4. As the keys, when in the holder, are covered except for portions of their handle ends 6, it is difficult to select the proper key without first swinging the keys to project out of the holder, as shown in dotted lines in the several views. To permit the ready rotation of the keys out of the holder I cut away the back portion of the holder at its two ends, as shown at 7, so that the handles 6 of the keys 4 project far enough to permit the handle parts to be pushed inwardly and cause the other ends 8 to be projected through the open side of the holder. The back portion 3 of the holder is rounded over, as best shown in Figs. 3 and 4, and, of course, closes the back of the holder.

I have found that frequently a person will wish to carry more than the four keys which can be contained in one of the holders 1. For increasing the capacity of a holder I provide simple means for hinging two of the holders 1 together. While this hinging means might consist of merely means for securing two of the holders 1 back to back, I prefer to so con-

nect the two holders that they will be yieldingly held together in such a manner that they can be separated slightly if need be. As shown, I provide a yielding tie member 9 consisting of a suitable spring member adapted to be threaded through one of the members 1 adjacent to its back 3, as shown in Fig. 2. This connecting member 9 consists preferably of a wire formed into hooks 10 at its ends and wound into spring form between its ends, as shown at 11. In connecting two of the holders 1 to form a double holder the connecting member 9 is threaded through the rear portion of one holder and its advance end is pulled out far enough so that the advance hook 10 can be hooked over the adjacent end of the holder, the hook 10 at the other end engaging the opposite end of the holder. Then the back of the other holder is slipped under one of the hooks 10 and the other end is pulled out far enough to let its hook snap into place around the opposite end of the back of the second holder.

As the connecting member 9 is made of spring wire commonly known as piano wire and as the hooks are relatively large and are formed quite rounded, the two holders are yieldingly held against separation. They are free to separate under the pressure of a finger and thumb, as indicated in dotted lines at 10a and 10b, pressed into the spaces 12 formed between the backs of the two holders by reason of the cut out portions 7.

It will be understood that if a person has a single unit 1 and wants to carry more keys than its capacity he can readily attach another unit, making a double holder by the use of one of the connectors 9. As shown in Fig. 4, the connector 9 acts as a hinge connection permitting the two single holders to lay flat against each other in compact rotation for carrying in the pocket.

In Figs. 7 to 9, inclusive, I have illustrated another method of connecting two unit holders to form a double holder.

As shown in the form of holder illustrated in Figs. 5, etc., the metal frame 2 may be covered with leather 13 which conforms in shape to the metal frame 2.

In the form shown in Figs. 7, etc., the metal frame is cut away at the back and comprises merely two metal side plates 14. The leather cover 13 in this form extends around as before and makes a back 15 to the holder. Instead of the removable yielding hinge member 9 I may sew the two cover members 13 together along the center line of the back, as shown at 16, and as these cover members are flexible the units can be readily folded upon each other, as shown in Fig. 9, to bring the double holder into a compact condition for pocket carrying.

For some uses the screw or bolt fasteners 5 have not proven satisfactory, as under some circumstances the screws may loosen and not

hold the parts together properly. As an improvement upon the bolt fasteners I have provided a removable fastener of very simple form which cannot loosen or fall out once it has been placed in position. This fastener consists of a U-shaped fastener 17, preferably made of a strip of spring metal such as steel and bent into U-form.

The two legs 18 and 19 extend out parallel from the connecting part 20 and one is preferably longer than the other. The longer leg 18 has its free end 21 bent inwardly to form a stop which is adapted to enter an opening 22 provided in the holder frame. The legs 18 and 19 are separated sufficiently so to receive the body of the holder between them when the connecting part 20 extends through the openings 23, in the holder, formerly occupied by the connecting bolts 5. As will be clear from Fig. 11, the stop 21 enters the hole 22 and prevents the retainer 17 from rotating out of its holding position. To remove the retainer 17 the arm 18 is sprung up to lift the stop 21 out of the opening 22, then the retainer is rotated to the dotted position shown in Fig. 10, that is, to extend over the narrow edge 24 of the holder and in which position it is easy to thread the retainer out of or into the opening 23. The rounded shape of the connecting part 20 of the retainer 17 makes it easy to remove or replace it.

While I have gone into specific detail in describing the constructions shown, it should be understood that I do not thereby limit or confine my invention to such specific details, as many modifications thereof will readily suggest themselves to one skilled in the art.

I claim:

1. A key holding device comprising two similar holders joined together along longitudinal sides, each holder having removable fasteners passing through each end thereof for removably holding keys, each holder cut away at each end adjacent to the other holder to provide opposite end openings into which the handles of keys project, said openings being adapted to receive a thumb and finger for convenience in turning the keys out of the holder.

2. A key holding device comprising two similar frames, each having removable key retainers at each end, means hinging the frames together along one side and permitting the two frames to be arranged in a single plane, the frames cut away at each end of the hinged side to provide opposite end openings into which the handles of the keys project, said end openings being adapted to receive a thumb and finger of a hand for convenience in rotating the keys on the fasteners for exposing the keys.

3. A key holder consisting of two similar frames, each formed of sheet metal to provide parallel sides spaced apart to receive

the keys between them, removable key fasteners at the ends of the frames passing through the sides thereof, the sides of each frame joined along the rear edges thereof and a yielding fastener passing through both frames at the rear edges thereof and hinging them together, both the frames cut away at their rear edges adjacent to the key fasteners to expose the handles of the keys, the adjacent cut away portions of the two frames providing notches at the ends of the holder for convenience in causing the keys to be projected from the holder.

4. A key holder of the kind described, comprising a frame having sides parts between which the keys can be placed, the side parts having registering openings, and a U-shaped key-retaining-member adapted to be threaded through said holes and through holes in the handles of keys, the legs of the retaining member adapted to contact with the said side parts, and means for locking said retaining member against accidental removal.

5. A key holder of the kind described, comprising a frame having side parts between which the keys can be placed, the side parts having registering openings, and a resilient key-retaining-member adapted to be threaded through said holes and through holes in handles of keys placed between said side parts, and means for preventing the accidental removal of said retaining member.

6. A key holder of the kind described, comprising a frame having side parts between which the keys can be placed, the side parts having registering openings, and a U-shaped resilient key - retaining - member adapted to be threaded through said holes and through holes in the handles of keys, the arms of said retaining member being arranged parallel with each other and spaced apart to receive the holder between them, the one arm having an inward projection adapted to enter an opening in the adjacent side part of the frame to prevent the rotation of the retainer.

7. A key holder of the kind described, comprising a frame having side parts between which the keys can be placed, the side parts having registering openings, and a U-shaped resilient key - retaining - member adapted to be threaded through said holes and through holes in the handles of keys, the arms of said retaining member being arranged parallel with each other and spaced apart to receive the holder between them, the side parts cut away at a point adjacent to said holes to permit the easy threading of the retaining member through said holes, one arm of the retainer adapted to enter an opening provided in the adjacent side part to prevent the rotation of the retainer after it has been placed.

8. A key holder having substantially rigid

parts, removable key retaining members at the ends of the parts adapted to pass through holes in the handles of keys for rotatably mounting the keys in the holder, the holder provided with oppositely arranged end openings into which the handles of keys project and adapted to receive a thumb and finger of a hand for convenience in rotating the keys upon their fasteners for exposing the keys.

9. A key holder having an elongated frame formed to present opposed end openings, means arranged at the ends of the holder for removably and pivotally securing keys in the holder with their handle ends projecting into said openings as and for the purpose specified.

10. A key holder consisting of two similar frames adapted to be arranged side by side and having side parts between which keys can be placed, removable key fasteners at the ends of the frames, passing through the sides thereof, and means yieldingly hinging the frames together along their adjacent sides, the frames cut away at the ends of their adjacent sides to permit the handles of the keys to project from the frames and to form openings for convenience in causing the keys to project from the frames.

In testimony whereof, I have hereunto set my hand, this 3rd day of June, 1927.

ALCADA F. DODSON.
